AMMONIA-COMPRESSOR.

1,264,043.

Specification of Letters Patent.

Patented Apr. 23, 1918.

Application filed November 10, 1917. Serial No. 201,339.

To all whom it may concern:

Be it known that I, GEORGE FERGUSON, a subject of the Queen of the Netherlands, residing at Apeldoorn, Province of Gelderland, in the Kingdom of the Netherlands, have invented certain new and useful Improvements in Ammonia-Compressors, of which the following is a specification.

This invention relates to improvements in ammonia compressors, proposing a construction which is provided with a water cooling jacket.

In the known constructions the provision of the water jacket has rendered the form of the cylinder complicated; and further, in casting, owing to the trapping of the air by the core of the water jacket, the metal of the cylinder assumes a somewhat porous character which renders liable a disadvantageous leakage of ammonia.

The principal object of the present invention is to overcome the above objections, *i. e.* to provide an ammonia compressor having a water jacketed cylinder wherein the cylinder is exceedingly simple in its construction and wherein there is no liability of leakage of the ammonia, this advantage being achieved by a peculiar construction and arrangement of parts whereby, in casting, the objectionable porous characteristic above mentioned is not developed and whereby all joints are conveniently and satisfactorily packed.

Further objects of the invention are to increase the efficiency of the compressor, to provide for easy access to the cylinder valves and to provide for the accurate alinement of the cylinder relatively to the crosshead guide and the stable support of the cylinder by the frame which is utilized in the construction of the water jacket.

With the above objects in view the invention consists in certain novel features of structure, combination and relation which will be set forth in detail as the description proceeds.

An embodiment of the invention is illustrated in the accompanying drawing; wherein:—

Figure 1 is a vertical longitudinal section of an ammonia compressor in which the features of the invention are incorporated.

Fig. 2 is a horizontal section on line I—I of Fig. 2.

Fig. 3 is a vertical cross-section on line 55 II—II of Fig. 1, and

Fig. 4 is a vertical cross-section on line III—III of Fig. 1.

Similar characters of reference designate corresponding parts throughout the several views.

The compressor cylinder 1 is closed at its ends by the outer and inner heads 2 and 3, the head 3 being provided with a suitable stuffing box 4 for the piston rod 5. The means for cooling the stuffing box has not been illustrated. The cylinder 1 is attached to the supporting frame 6 by a series of bolts 7, two of which are shown in Fig. 2. The head 3 has a marginal flange 8 which fits within a recess of the frame, thereby to center said head relatively to the frame. The frame has a projecting or overhanging portion which encircles a portion of the cylinder and is provided at its outer end with internal annular ribs 9 and 10 for the support of the cylinder. The ribs 9 and 10 delimit the intermediate portion of the external wall of the water jacket and the ribs are fitted to the outer portions of said external wall, the joints between the ribs and the adjacent surfaces of the water jacket being suitably packed. The exact centering of the cylinder 1, the stuffing box 4, and crosshead-guide 11 is thus secured. The cylinder is fixed in position by the frame and does not require a special support on the foundation or bed.

The cylinder is provided along its upper ends with inlet openings 12 which are controlled by suitable suction valves (not shown) and along its lower side with outlet openings 13 which are controlled by suitable pressure valves (not shown).

The inlet conduit (not shown) is connected with the inlet nipple 14 and the outlet conduit (not shown) is similarly connected with the outlet nipple 15. The nipples 14 and 15 are located beyond the frame, preferably in the plane of the line II—II.

The openings 12 are located at the ends of an inlet duct or chamber 16 which is disposed lengthwise and externally of the cylinder and the openings 13 are similarly located at the ends of an outlet duct or chamber 17. The nipples 14 and 15 communicate with the respective ducts or chambers 16 and 17, said nipples being preferably located in

the same plane as the valves which adjoin the head 2. The frame 6 is provided with openings 18 and 19 through which convenient access may be had to the valves which 5 adjoin the head 3.

The water jacket has its external wall cast in part with the cylinder and in part with the frame. The outer portions of the said external wall are cast with the cylinder and 10 the intermediate portion of said wall is cast with the frame, and, as above pointed out, constitutes the portion of the frame which is located between the ribs 9 and 10. This 15 peculiar construction of the external wall of the water jacket permits of the escape of air without difficulty from the jacket space during the casting operation.

The water jacket is provided with an inlet opening 20 and with a discharge opening 21, 20 these openings being so arranged that the upper portion of the cylinder, together with the ammonia inlet valves (not shown), the nipple 14 and the duct or chamber 16, is situated above the level of the cooling water 25 (Fig. 4). The ammonia as it comes from the evaporator has a temperature below the freezing point and the parts above the level of the cooling water are covered by a layer of snow or ice which has an insulating effect. 30 The purpose of the location of the openings 20 and 21 as described is to prevent the loss of cold which would take place in case the upper portion of the cylinder and the parts associated therewith were in contact 35 with water, instead of with air as in the construction according to the invention. That is to say if the upper portion of the cylinder were in contact with water a considerable heat transmission between such cylinder portion 40 and the cooling water would be set up with a consequent considerable loss of cold. The exposure of the upper portion of the cylinder to air avoids such loss because air transmits heat much less effectively than 45 water. The manner of cooling which the invention provides for consequently results in an increase in the efficiency of the compressor.

The lower portion of the cylinder and the 50 parts associated therewith, through which the hot compression gases flow, are surrounded by the cooling water.

Having thus described my invention, I claim—

55 1. In an ammonia compressor, a cylinder, a supporting frame having an end portion which encircles a portion of the cylinder, and a water jacket having the end portions of its external wall cast with the cylinder and the 60 intermediate portion of said wall cast with the frame, the frame having at its outer end

a pair of spaced internal annular ribs for centering and supporting the cylinder, and having the said intermediate portion of the external wall of the water jacket located between said ribs. 65

2. In an ammonia compressor, a cylinder, a supporting frame having an end portion which encircles a portion of the cylinder, the cylinder having a flanged head at its inner 70 end and the frame having a recess in which said head fits, thereby to center the cylinder, means for securing the cylinder adjacent said flanged head to said frame, and a water jacket having the end portions of its external wall cast with the cylinder and the intermediate portion of said wall cast with the frame, the frame having at its outer end a pair of spaced internal annular ribs for centering and supporting the cylinder, and 75 having the said intermediate portion of the external wall of the water jacket located between said ribs.

3. In an ammonia compressor, a cylinder, a supporting frame having an end portion 80 which encircles a portion of the cylinder, and a water jacket having the end portions of its external wall cast with the cylinder and the intermediate portion of said wall cast with the frame, the frame having at its outer end a pair of spaced internal annular ribs for centering and supporting the cylinder, and having the said intermediate portion of the external wall of the water jacket located between said ribs, the cylinder having inlet and outlet 85 valves adjacent both ends thereof and the portion of the frame which encircles the cylinder having openings through which access may be had to the valves at the inner 90 end of the cylinder. 95

4. In an ammonia compressor, a cylinder, a supporting frame having an end portion which encircles a portion of the cylinder, the cylinder having inlet valves along its upper side, and a water jacket having the end portions of its external wall cast with the cylinder and the intermediate portion of said wall cast with the frame, the frame having at its outer end a pair of spaced internal annular ribs for centering and supporting the cylinder, and having the said intermediate portion of the external wall of the water jacket located between said ribs, the water jacket having inlet and outlet nipples so located that the upper portion of the cylinder is 110 located above the cooling water. 115

In testimony whereof I have hereunto set my hand.

GEORGE FERGUSON.
